UNITED STATES PATENT OFFICE.

ROBERT F. RUNGE, OF FOREST HILLS, NEW YORK, ASSIGNOR TO THE HESS-BRIGHT MANUFACTURING COMPANY, A CORPORATION OF DELAWARE.

BALL CAGE OR RETAINER FOR BALL BEARINGS.

Application filed October 25, 1923. Serial No. 670,652.

To all whom it may concern:

Be it known that I, ROBERT F. RUNGE, a citizen of the United States, residing at Forest Hills, in the county of Queens and State of New York, have invented certain new and useful Improvements in Ball Cages or Retainers for Ball Bearings, of which the following is a specification, reference being had therein to the accompanying drawings.

This invention relates to ball retaining separators or cages for use in ball bearings and has for an object to provide a strong and efficient sheet metal device of this character which will have long life in service and which will not unduly wear the balls associated with it in the bearing. The cage is made of two similar drawn or pressed sheet metal rings. These are provided with recesses or sockets forming ball pockets and are rigidly and permanently connected together. The entire ball engaging surfaces of the walls surrounding each pocket are formed from the face of the blank as distinguished from previously known structures in which the cut edges of the notches in the ring and web contact with the balls. Such cut edges unless carefully smoothed have a tendency to scratch and mar the highly polished surfaces of the balls. The drawing operation as I practice it leaves the pocket surfaces smooth.

In the drawings forming a part of this application an illustrative example of my improved cage is shown, in which drawings—

Figure 1 is a perspective view of one of the halves or twin members of the cage.

Fig. 2 is an elevation looking at this from the side which is engaged by the other half or twin.

Fig. 3 is an edge view.

Fig. 4 is a section of the completed cage, and

Fig. 5 shows a blank prior to the drawing operations.

A drawn sheet metal ring is shown comprising a substantially cylindrical portion, 7, and radially disposed lugs or web sections, 8. The web sections of two of these rings are rigidly and permanently connected together in some suitable manner, rivets, 9, being shown in the illustration passing through suitably formed openings, 10. The ball pockets, 11, are formed in the cylind-

rical portion, 7, of the ring and between the lugs or web sections, 8. The edges of the ring body and the web sections are turned outwardly at the pockets in a substantially continuous flange. The portion, 12, turned up from the body of the ring merges into the portions, 13, turned up from the two adjacent web sections, 8. It will be seen that the entire ball engaging surfaces of the walls surrounding these pockets, 11, are formed from the face of the blank. In the illustration they are continuous with the inner face, 14, of the ring or body portion which is also continuous with the face, 15, of the ring which engages a similar face 70 of its companion ring or twin.

It will be noted that the ball pockets are located between the radially disposed lugs or web sections and extend into the cylindrical ring portion or body. The metal of 75 this latter portion is drawn toward the respective lugs, the opposite edge presenting a drawn sinuous outline curving inwardly toward the lugs and outwardly from the pockets. When the ring is drawn from a flat blank, 16, such as that shown in Fig. 5, the walls, 17, surrounding the central opening, 18, constitutes the edge, 19, of the finished ring which assumes during the drawing operation the sinuous character 80 above mentioned. This adds to the strength, lightness and pleasant appearance of the structure when assembled for use in a ball bearing and obviates the necessity of specially forming this edge other than to punch 85 out the hole, 18, in the blank.

I claim as my invention:

1. A ball cage comprising a pair of sheet metal rings each having a cylindrical body portion and radially disposed lugs or web sections, the body portion being recessed between adjacent webs and the body at the region of the recess and adjacent edges of the lugs having turned over edges, such turned over edges forming a continuous 100 flange.

2. A ball cage comprising a pair of similar sheet metal rings formed with radially disposed lugs or web sections these being rigidly fastened together, the rings being 105 formed with recesses between the lugs or web sections, the edges of the ring and web sections being turned outwardly at the recesses.

3. A ball cage comprising a pair of drawn 110

sheet metal rings each having a substantially cylindrical portion carrying radially disposed lugs or web sections, there being ball pockets between these extending into the cylindrical portion, the metal of the latter portion being drawn toward the respective lugs, whereby the opposite edge presents a

drawn sinuous outline curving inwardly toward the lugs and outwardly from the pockets.

10

In testimony whereof, I have affixed my signature hereto.

ROBERT F. RUNGE.
